(57) **CLAIM**

The ornamental design of a three tier shower caddy with rectangular shelves, as shown and described.

DESCRIPTION

FIG. 1 is a perspective view of a three tier shower caddy with rectangular shelves in accordance with my design.

FIG. 2 is a top plan view thereof;

FIG. 3 is a front elevational view thereof;

FIG. 4 is a side elevational view viewed from the left side in FIG. 1, with the right side elevational view being a mirror image thereof;

FIG. 5 is a rear elevational view; and,

FIG. 6 is a bottom plan view.
